UNITED STATES PATENT OFFICE.

JOHN MOTLEY MOREHEAD, OF CHICAGO, ILLINOIS.

GAS-ANALYSIS APPARATUS.

No. 824,999.

Specification of Letters Patent.

Patented July 3, 1906.

Application filed June 17, 1905. Serial No. 265,797.

To all whom it may concern:

Be it known that I, JOHN MOTLEY MOREHEAD, a citizen of the United States; residing at Chicago, in the county of Cook and State 5 of Illinois, have invented certain new and useful Improvements in Gas-Analysis Apparatus, of which the following is a specification.

In the analysis of industrial gas mixtures such as illuminating, producer, furnace, and 10 flue gases certain constituents—such as carbon dioxid, acetylene, ethylene, oxygen, and carbon monoxid—are usually determined by successively passing a measured volume of the gas into different vessels containing reagents which will absorb one or more of the 15 constituents—such as solutions of potassium hydroxid, bromin, pyrogallic acid, and cuprous chlorid—the percentage of each constituent being determined by the contraction 20 in volume of the sample after each absorption. The hydrogen and methane are then determined by mixing the residual gas with oxygen and air and igniting the mixture in an explosion-burette, the hydrogen being 25 thereby burned to water and the carbon to carbon dioxid, which is then absorbed by potassium hydroxid, the amount of each being determined by the successive contractions. The repeated transfer of the gas 30 sample between the several vessels requires considerable skill, is a slow operation, and involves the risk of loss of a portion of the sample on account of the many cocks and joints in the apparatus.

35 The present apparatus comprises a graduated burette by which the gas sample is measured and in which each step of the analysis is effected, the several reagents being successively introduced therein. The burette is 40 provided at its upper end with a three-way cock, which controls passages leading to a funnel for the introduction of the reagents, a wash-bottle, and a storage-bulb with its control-bottle. At the lower end of the burette 45 is a bulb having an outlet to a three-way cock which controls a water-sealed outlet and a rubber tube leading to a leveling-bottle.

50 Referring to the accompanying drawing, the figure is a perspective view of the complete apparatus.

The burette 1 is of ordinary form, preferably holding one hundred cubic centimeters and graduated in tenths. It is held in a vertical position by clamps 2 on a standard 3.

55 At the upper end of the burette is a three-way

cock 4, which controls a tube 5, carrying a removable funnel 6 and a horizontal passage connected by a rubber coupling 7 to another three-way cock 8. The cock 8 controls a rubber tube 9, leading to a wash-bottle 10, and the upper end of a gas-storage bulb 11, to the lower end of which is connected a rubber tube 12, leading to a control-bottle 13.

The lower end 14 of the burette is enlarged and has a tubular extension containing a 65 three-way cock 15. This cock controls the rubber tube 16 of the leveling-bottle 17 and has a hollow plug with a tubular extension, which is normally sealed by water in the beaker 19. Platinum electrodes 20 21 are 70 sealed into the burette near its upper end.

The bottles 10, 13, and 17 are normally supported by a shelf 22, fixed upon the upper end of the standard 23. The bottle 17 may also be placed on the table 23.

In preparing the apparatus for an analysis the bottles 10, 13, and 17, the burette, storage-bulb 11, and pipes are filled with water, the funnel 6 is removed from the upper end of the burette, and the pipe 5 is put in communication with the source of gas. The cocks 4 and 15 are turned to allow the gas to pass into the upper end of the burette, while the water therein runs through the stem 18 of the lower cock into the beaker. When the 85 burette is filled with gas, the cock 4 is closed, the connection is removed from the pipe 5, and the funnel 6 replaced thereon and filled with water. Bubbles of gas are then allowed to escape by opening the cock 4 until the burette contains one hundred cubic centimeters 90 at atmospheric pressure, as controlled by the leveling-bottle 17, which is put into communication with the lower end of the burette by turning the cock 15. To determine the 95 percentage of carbon dioxid in the sample, the funnel is drained except for a small layer of water in the bottom, the upper cock is again closed, and the lower cock is turned to connect the burette with the beaker. The 100 standard potassium-hydroxid solution is introduced into the funnel and allowed to drain slowly into the burette until the funnel is nearly empty, whereupon the cocks 4 and 8 are turned to allow water to run from the 105 wash-bottle 10 through the connections 9 7, and through the burette, for a period of about ten seconds. The cock is then closed, the funnel removed, rinsed, replaced, and re-filled with water. The leveling-bottle 17 is 110

again connected with the burette, and the volume of gas at atmospheric pressure measured, the loss being equal to the amount of carbon dioxid in the sample. The illuminants in the gas—for example, acetylene and ethylene—are similarly determined by successively introducing bromin and potassium hydroxid into the burette. This reaction evolves considerable heat, which may largely increase the volume of the gas. The bulb or enlargement 14 at the lower end of the burette acts as a liquid-reservoir and prevents any possible loss of the gas due to this expansion, the capacity of this bulb being sufficient to permit the gaseous contents of the relatively narrow burette to materially expand without expelling all of the water through the stem 18 of the lower cock. The oxygen is then absorbed by a solution of potassium pyrogal late and the carbon monoxid by a solution of cuprous chlorid, the burette and funnel being washed after each absorption. To determine the unabsorbed gases—hydrogen, methane, and nitrogen—the cocks 8, 4, and 15 are turned to put the burette in communication with the bulb 11 and bottles 13 and 17. By raising the bottle 17 all of the remaining gas but ten cubic centimeters is forced out of the burette into the bulb 11, displacing the water therein into the bottle 13. The cock 8 is then closed, the funnel 6 removed, a measured amount of air and oxygen introduced into the burette through the pipe 5 and cock 4, and the mixture in the burette exploded by an electric spark passed between the electrodes 20 21. The amount of gas in the burette is then measured, the carbon dioxid resulting from the explosion absorbed by potassium hydroxid, the gas remeasured, and the percentage of hydrogen, methane, and nitrogen determined from the successive losses in volume. In case the explosion is unsatisfactory or to check the analysis another portion or portions of gas may be introduced into the burette from the storage-bulb 11.

With this apparatus each of the constituents of ordinary gas mixtures may be quickly determined, with a probable error of one part in five hundred. The gas undergoing analysis is retained in the burette and is under a water seal throughout. The risk of loss to portions of the sample or of introducing air into it is thereby eliminated.

55 I claim—

1. A gas-analysis apparatus, comprising a graduated burette, a funnel and a wash-bottle connected to the upper end of the burette, and a leveling-bottle connected to the lower end of the burette, as set forth.

2. A gas-analysis apparatus, comprising a graduated explosion-burette having electrodes, a funnel and a storage-bulb connected to the upper end of the burette, and a leveling-bottle connected to the lower end of the burette, as set forth.

ing-bottle connected to the lower end of the burette, as set forth.

3. A gas-analysis apparatus, comprising a graduated explosion-burette having electrodes, a funnel and a storage-bulb connected to the upper end of the burette, a control-bottle connected to the lower end of the bulb, and a leveling-bottle connected to the lower end of the burette, as set forth.

4. A gas-analysis apparatus, comprising a burette having electrodes, a three-way cock at the upper end of the burette, a funnel and a second three-way cock controlled thereby, a wash-bottle and a storage-bulb controlled by the second three-way cock, and a leveling-bottle connected to the lower end of the burette, as set forth.

5. A gas-analysis apparatus, comprising a graduated burette, a funnel at the upper end of the burette, and a separate leveling-bottle and water-sealed outlet connected to the lower end of the burette, as set forth.

6. A gas-analysis apparatus, comprising a burette, a funnel and a wash-bottle connected to the upper end of the burette, and a separate leveling-bottle and water-sealed outlet connected to the lower end of the burette, as set forth.

7. A gas-analysis apparatus, comprising a burette having electrodes, a three-way cock at the upper end of the burette, a funnel and a second three-way cock controlled thereby, a wash-bottle and a storage-bulb controlled by the second three-way cock, and a separate leveling-bottle and water-sealed outlet connected to the lower end of the burette, as set forth.

8. A gas-analysis burette for effecting exothermic reactions, having a bulbed lower end to act as a liquid reservoir and a liquid-sealed outlet leading from the bulb, the bulb capacity being sufficient to permit the gaseous contents of the burette to materially expand without expelling the liquid from the seal, as set forth.

9. A gas-analysis apparatus, comprising a burette having a bulbed lower end, a separate liquid-sealed outlet and leveling-bottle connected to the bulb, and a funnel at the upper end of the burette, as set forth.

10. A gas-analysis apparatus, comprising an explosion-burette having electrodes and a bulbed lower end, a separate liquid-sealed outlet and leveling-bottle connected to the bulb, a funnel and a storage-bulb connected to the upper end of the burette, and a control-bottle connected to the storage-bulb, as set forth.

In testimony whereof I affix my signature in presence of two witnesses.

JOHN MOTLEY MOREHEAD.
